UNITED STATES PATENT OFFICE.

DANIEL L. HARRIS, OF WICHITA, KANSAS.

HORSESHOE.

1,174,860.

Specification of Letters Patent. Patented Mar. 7, 1916.

Application filed April 23, 1915. Serial No. 23,454.

To all whom it may concern:

Be it known that I, DANIEL L. HARRIS, a citizen of the United States, residing at Wichita, in the county of Sedgwick and 5 State of Kansas, have invented new and useful Improvements in Horseshoes, of which the following is a specification.

This invention relates to improvements in horse shoes.

10 One object of the invention is to provide an improved horse shoe which serves to fully protect the hoof and without pressure on the frog.

Another object is to provide clamps of 15 improved construction for securing the shoe to the hoof and render it unnecessary to nail the shoe to the hoof; another object being to provide the shoe with studs to enter the hoof and coat with the clamps in securing the shoe on the hoof.

The invention consists in the construction, combination and arrangement of devices hereinafter described and claimed.

In the accompanying drawings, Figure 1 25 is a side elevation, partly in section, of a horse shoe constructed in accordance with my invention. Fig. 2 is a plan of the same. Figs. 3 and 4 are detail sectional views.

The horse shoe 1 is flat, conforming to the 30 shape of the bottom of the hoof, and on its upper side presents a flange 2 to bear under and extend around the front and sides of the hoof, the shoe being formed with a depression 3 within the flange which prevents 35 the shoe from pressing on the frog, the depression being formed by a web or bottom 4 which extends entirely across the lower side of the shoe so that the hoof is entirely protected from contact with the ground and 40 from injury by any object on which the horse may step. The rear flange 5 excepting the channels 6 which are between the ends of said flange and rear ends of the flanges 2 and 1 form an outlet for water which may 45 get in the recess between the bottom of the shoe and the hoof.

At the toe and heel of the shoe, in the undersides are dove tail grooves 7 which receive correspondingly shaped heads 8 and 50 detachable calks 9, the said calks being secured in the said grooves by dove tail blocks 10 which are detachably fitted in the outer ends of said grooves and are secured in place by screws 11. When any of the calks are 55 worn or broken they can be readily removed

and new ones substituted, thus greatly prolonging the life of the shoe.

The shoe is provided with a toe clamp 12 which is hinged or pivotally connected at its lower front end of the toe of the shoe 60 as at 13 and has an upwardly extending tongue 14 provided with a slot 15, said toe clamp being also provided with an outwardly extending lug 16 at a point a suitable distance from the front end of said 65 slot. I also provide a rear clamp 17 which comprises a shield 18 to bear on the front of the hoof and behind the tongue and a pair of longitudinally adjustable metallic binder straps 19 which are adjustably 70 mounted in the ends of the shield by being passed through openings 20 thereof, the rear ends of said binder straps have in-turned ends forming lugs 21 to engage in notches 22 near the heel of the shoe, the 75 front ends of the said binder straps having outwardly extending lugs 23 connected together by an adjusting bolt 24 which has a winged nut 25. Hence the binder straps of the heel clamp can be adjusted as required 80 to firmly secure the heel of the shoe to the corresponding portion of the hoof. The shield 18 also has a lug 27 which extends outwardly through the slot 15 of the toe clamp and is connected by an adjustable 85 bolt 28 to the lug 16 of the toe clamp so that the heel clamp may be adjusted on the hoof as required.

To prevent the shoe from moving on the hoof I provide the shoe at points near the 90 toe and heel with upwardly extending studs 29, which may be detachably fitted to the shoe and which engage recesses made in the hoof when attaching the shoe thereon.

It will be understood from the foregoing 95 description and by reference to the drawing that my improved shoe may be readily attached to the hoof without the necessity of nailing it thereto and that it may be adjusted as required and that moreover it 100 serves to effectually protect the horse's hoof from injury.

Having thus described my invention I claim:—

1. A horse shoe having a toe clamp to 105 bear on the front of the hoof, pivotally connected to the shoe, said toe clamp having a slot and a lug at one end of said slot, a heel clamp detachably connected to the heel of the shoe and detachably connected to the 110

- toe clamp, said heel clamp comprising a shield for arrangement on the front of the hoof and behind the toe clamp and having a lug which operates in the slot of the toe clamp, an adjusting bolt connecting said lugs, and binder straps detachably engaged with the shoe, slidably engaged with the shield and adjustably connected to each other.
- 10 2. A horse shoe having a toe clamp to bear on the front of the hoof, pivotally connected to the shoe, said toe clamp having a slot and a lug at one end of said slot, a heel clamp detachably connected to the heel of the shoe and detachably connected to the toe clamp, said heel clamp comprising a shield for arrangement on the front of

the hoof and behind the toe clamp and having a lug which operates in the slot of the toe clamp, an adjusting bolt connecting 20 said lugs, and binder straps detachably engaged with the shoe, slidably engaged with the shield and adjustably connected to each other, the said shield having openings through which said binder straps slidably 25 pass and an adjusting bolt being provided to connect the front ends of said binder straps.

In testimony whereof I affix my signature in presence of two witnesses.

DANIEL L. HARRIS.
